AIR CONDITIONING APPARATUS

Alfred Armstrong and Michael D. Ulich, East Longmeadow, Mass., assignors to Westinghouse Electric Corporation, East Pittsburgh, Pa., a corporation of Pennsylvania

Application November 25, 1958, Serial No. 776,296

6 Claims. (Cl. 62—324)

This invention relates to air conditioning apparatus and more particularly to a compression refrigeration air conditioning unit adapted for regulation of humidity content of the conditioned air.

In maintaining air conditions within an enclosure that are comfortable to humans, it is necessary that the moisture content of the air, as well as the air temperature, be controlled. High air temperature is generally accompanied by high humidity and both conditions can be corrected, or rendered satisfactory, by passing the air through an air cooling unit, because dehumidification to an acceptable level generally accompanies cooling. There are, however, periods during which the air temperature is at an acceptable level but the air nevertheless contains a high percentage of moisture, so that discomfort is experienced. Under these conditions dehumidification, accompanied by reduction of the sensible heat in the air, is desirable.

This invention relates to a refrigerating system or circuit, the operation of which can be altered or modified to effect substantially pure dehumidification of air, i.e. dehumidification without reduction of the sensible heat in the conditioned air. Moreover, this invention requires only simple additions to and changes in a refrigerating system and, consequently, may be utilized in low cost air conditioning units, such as those employed to condition one or more rooms in a private residence.

In accordance with this invention, both the indoor air and outdoor air portions of the air conditioning unit are equipped with two heat exchangers. A single compressor, generally disposed in the outdoor air portion of the unit, is employed to circulate, or pump, refrigerant fluid through these several heat exchangers. One indoor heat exchanger and one outdoor heat exchanger are connected to the compressor by means including a refrigerant flow reversing device which selectively directs refrigerant through the outdoor heat exchanger to the indoor heat exchanger or through the indoor heat exchanger to the outdoor heat exchanger, whereby heat is selectively absorbed by one of said heat exchangers and dissipated by the other of said heat exchangers. This enables this indoor heat exchanger to operate either as an evaporator for cooling indoor air or as a condenser for heating indoor air.

Further, in accordance with the invention, the other two heat exchangers, i.e., the other indoor heat exchanger and the other outdoor heat exchanger, are connected to the compressor in parallel refrigerant flow relationship to the two reversible heat exchangers in such a manner that said other indoor heat exchanger always functions as an evaporator to cool indoor air, and said other outdoor heat exchanger always functions as a condenser to dissipate heat to outdoor air.

The object of connecting the several heat exchangers in the aforesaid manner is to enable both indoor heat exchangers to function as evaporators for the purpose of cooling indoor air when high temperature conditions, either with or without high humidity, are encountered,

and further, to enable one indoor heat exchanger to function as a condenser for reheating air that has been cooled and dehumidified by the other indoor heat exchanger, so that the indoor air is dehumidified without sensible cooling when only high humidity conditions are encountered.

The several features, objects and advantages of the invention are elucidated in the following detailed description of which the accompany drawing forms a part and wherein:

Fig. 1 is a simplified illustration of an air conditioning unit embodying this invention;

Fig. 2 is a schematic refrigerant circuit diagram of a refrigeration system embodying the invention; and

Fig. 3 is another diagram of the refrigeration system showing a different operating condition thereof.

The air conditioning unit embodying the invention includes a casing 11, having a partition 12 therein that divides the unit into an indoor section 13 and an outdoor section 14. The casing 11 is adapted to be mounted within an opening, such as a window, of a building wall 15 in such a manner that the indoor section, 13, communicates with air to be conditioned in a room or other enclosure. The outdoor section, 14, communicates with outdoor air, i.e. air outside the conditioned enclosure. The indoor section 13 contains first and second heat exchangers 16 and 17 which are arranged in facing relationship adjacent one another. Air to be conditioned enters the indoor section of the unit through an inlet opening 18 and is circulated by air propelling means, such as a motor driven propeller fan 19, over, or through, first indoor heat exchanger 16 and then indoor heat exchanger 17, and is returned to the conditioned enclosure through an outlet 20. Moisture that is condensed from the air as a result of cooling falls into a collection trough 21 and is conveyed from the conditioned enclosure by suitable drain means (not shown).

Heat is absorbed from and/or dissipated to the outdoor air by first and second outdoor heat exchangers 22 and 23 located within outdoor air section 14 of the unit. These heat exchangers are also preferably disposed in face-to-face relationship adjacent one another. Outdoor air is circulated over heat exchangers 22 and 23 by suitable air propelling means, such as a motor driven propeller fan 24.

The several heat exchangers form part of a compression refrigeration system, which includes a compressor 25 preferably located in the outdoor section of the unit. The compressor 25, in accordance with conventional practice, is preferably enclosed within a sealed casing which also houses the motor for driving the compressor. As best shown in Fig. 2, the compressor 25 includes conduit means defining an inlet 26 and an outlet 27 for the compressor.

The compressor 25 is adapted to pump, or convey, refrigerant fluid through two parallel refrigerant flow paths, each of which paths includes one indoor heat exchanger and one outdoor heat exchanger. The first flow path is conventional, in that a discharge conduit 28 conveys refrigerant from the compressor outlet 27 to the first outdoor heat exchanger 22, wherein heat is transferred to the outdoor air and refrigerant is condensed. The outdoor heat exchanger 22 is connected to the first indoor heat exchanger 16 by conduit means including a small bore restrictor tube 29. The pressure of the refrigerant flowing through tube 29 is progressively reduced and the refrigerant is thereafter evaporated at low pressure in the indoor heat exchanger 16 to absorb heat from indoor air. Vaporous refrigerant is returned from heat exchanger 16 to the compressor inlet 26 via a suction conduit 30. Outdoor heat exchanger 22 functions as a condenser and indoor heat exchanger 16 functions as an evaporator in this first refrigerant flow path.

The other refrigerant flow path serviced by the compressor 25, and which is connected in parallel flow relationship with the above-described flow path, includes outdoor heat exchanger 23 and indoor heat exchanger 17. In accordance with this invention, the latter heat exchangers are connected to the compressor 25 by means including a valve, indicated generally by the reference numeral 31, for selectively directing, or routing, refrigerant first through the outdoor heat exchanger 23 and then through the indoor heat exchanger 17 or first through the indoor heat exchanger 17 and then through the outdoor heat exchanger 23. In connection with this reversible refrigerant flow path it is to be noted that the heat exchangers 17 and 23 are connected by means including a bidirectional expansion device, such as a small bore restrictor tube 32. The tube 32 is adapted to effect reduction in pressure of refrigerant flowing therethrough, regardless of the direction of refrigerant flow.

The valve 31 determines whether refrigerant is directed first to the outdoor heat exchanger 23 or the indoor heat exchanger 17. For this purpose, the valve 31 includes a diverting chamber 33, which is connected to the compressor outlet 27 by a conduit 34 and is connected to the compressor inlet 26 by another conduit 35. The heat exchangers 17 and 23 are adapted to be connected to the diverting chamber 33 through conduits 36 and 37, respectively, as determined by the position of a slide 38 in the valve chamber 33. The slide 38 is movable to two positions: In one position, which is shown in Fig. 2, the compressor outlet 27 is connected to outdoor heat exchanger 23 by conduits 34 and 37 and the compressor inlet 26 is connected to indoor heat exchanger 17 through conduit 35, valve chamber 33 and conduit 36. In the other position of the slide 38 (shown in Fig. 3) the compressor outlet 27 is connected to indoor heat exchanger 17 through conduit 34 and conduit 36 and the outdoor heat exchanger 23 is connected to the compressor inlet 26 through conduit 37, valve chamber 33 and conduit 35.

The first position of the valve slide 38 (Fig. 2) directs refrigerant through the second parallel flow path in such a manner that outside heat exchanger 23 functions as a condenser and inside heat exchanger 17 functions as an evaporator. This position will hereinafter be referred to as the "cool" position of the valve 31, inasmuch as when the valve is so positioned, indoor heat exchanger 17 absorbs heat from and cools indoor air conveyed thereover. The second position of slide 38 (Fig. 3) will be referred to as the "dehumidify" position of the valve 31, inasmuch as when the valve is in this position indoor heat exchanger 17 functions as a condenser to reheat indoor air after it has passed over indoor heat exchanger 16.

Operation

When high temperature and high humidity conditions are jointly encountered, and it is therefore desirable to both cool and dehumidify air within the conditioned space, the valve 31 of the refrigerating system is set to its "cool" position of Fig. 2. With the refrigerating system thus conditioned, both indoor heat exchangers 16 and 17 function as evaporators and absorb heat from indoor air circulating thereover. Reducing the air temperature causes moisture to be condensed from the air, and this moisture is collected in trough 21 and conveyed outside the conditioned enclosure. The heat absorbed from the indoor air is dissipated to the outdoor air by heat exchangers 22 and 23, both of which function as condensers in the refrigerating circuit.

If dehumidification only is desired, as when the air temperature is at or below an acceptable level but the humidity content of the indoor air is too high for comfort, the unit is operated with valve 31 in the "dehumidify" position of Fig. 3. Under this condition of operation, indoor heat exchanger 16 continues to function as an evaporator to remove heat and, consequently, condense

moisture from the outdoor air. Indoor heat exchanger 17, however, functions as a condenser and reheats air leaving indoor heat exchanger 16 to a temperature at or slightly above the temperature of indoor air entering the unit. The indoor air is, therefore, dehumidified without sensible cooling. Under this condition of operation outdoor heat exchanger 22 continues to function as a condenser to dissipate heat absorbed in the indoor heat exchanger 16. Outdoor heat exchanger 23, however, functions as an evaporator to absorb heat from the outdoor air, which heat is added to the indoor air by heat exchanger 17 to replace the heat extracted from the indoor air by heat exchanger 16.

The refrigeration system employed in practicing this invention utilizes more or less standard equipment generally found in low-cost, unit type air conditioners. For example, in the conventional window-mounted air conditioning unit designed solely for indoor air cooling the outside heat exchanger (condenser) is generally physically larger than the indoor heat exchanger (evaporator). This relationship is maintained in the air conditioning unit utilizing this invention and, moreover, the relationship is employed to advantage. When operating to dehumidify indoor air (Fig. 3), indoor heat exchanger 17 functions as a condenser for part of the system and, because it is physically smaller than the outdoor heat exchanger 23, which functions as a condenser during cooling only operation, considerable head pressure is built up in indoor heat exchanger 17 and it operates at a higher temperature for more effective reheating of the indoor air. This effect tends to offset the difficulty of obtaining heat from outdoor air, which is generally at or below indoor air temperature when dehumidification only is desired.

Arranging the outdoor heat exchangers 22 and 23 in the order or relation with respect to the direction of outdoor air flow shown in the drawings, while not essential, is desirable. When the unit is operating to only dehumidify indoor air, the outdoor air is passed first over outdoor heat exchanger 22, which is functioning as a condenser, and then over outdoor heat exchanger 23, which is functioning as an evaporator. By moving outdoor air first over the warmer of the two outside heat exchangers 22 and 23, the likelihood of the exchanger that is functioning as an evaporator becoming frosted over is materially reduced. In addition, heat extracted from the indoor air to cause moisture to be condensed therefrom can be absorbed by outdoor heat exchanger 23 as it is dissipated from outdoor heat exchanger 22. This enables the air conditioning unit to be utilized as a dehumidifier even when outdoor air temperature drops considerably below the desired indoor air temperature and but little heat is available from the outdoor air for reheat purposes.

Only a simple reversing valve need be provided in the refrigeration circuit in order to permit the change-over from cooling to pure dehumidification and back to cooling. The valve 31 is, of course, illustrated diagrammatically, and, as is well understood in the art, some means, such as a manually actuated knob or electric solenoid, would be provided for moving the valve slide 38 in accordance with the wishes of the user of the unit, or automatically in accordance with temperature and humidity conditions within the conditioned enclosure.

While the invention has been shown in but one form, it will be obvious to those skilled in the art that it is not so limited, but is susceptible of various changes and modifications without departing from the spirit thereof.

What is claimed is:

1. In air conditioning apparatus including a compression refrigeration system, a compressor, first and second indoor heat exchangers, first and second outdoor heat exchangers, means providing a first refrigerant flow path from said compressor through said first outdoor heat exchanger to said first indoor heat exchanger and back to said compressor, and means including a reversing valve

providing a second refrigerant flow path parallel to said first refrigerant flow path and adapted to selectively direct refrigerant from said compressor through said second outdoor heat exchanger to said second indoor heat exchanger or through said second indoor heat exchanger to said second outdoor heat exchanger, whereby heat is selectively absorbed in one of said second heat exchangers and dissipated by the other of said second heat exchangers.

2. In air conditioning apparatus including a compression refrigeration system, a compressor, an indoor heat exchanger, an evaporator, means for directing air to be conditioned first over said evaporator and then over said indoor heat exchanger, a condenser, an outdoor heat exchanger, means for directing outside air first over said condenser and then over said outdoor heat exchanger, conduit means for routing refrigerant from said compressor through said condenser to said evaporator and back to said compressor, and means including a reversing valve for selectively routing refrigerant from said compressor through said outdoor heat exchanger to said indoor heat exchanger or through said indoor heat exchanger to said outdoor heat exchanger, whereby said indoor heat exchanger can be connected in parallel refrigerant flow relationship with either said evaporator or said condenser.

3. In air conditioning apparatus including a compression refrigeration system, a compressor, an indoor heat exchanger, an evaporator arranged in face-to-face relationship with said indoor heat exchanger, means for directing air to be conditioned first over said evaporator and then over said indoor heat exchanger, a condenser, an outdoor heat exchanger arranged in face-to-face relationship with said condenser, means for directing outside air first over said condenser and then over said outdoor heat exchanger, conduit means for routing refrigerant from said compressor through said condenser to said evaporator and back to said compressor, and means including a reversing valve for selectively routing refrigerant from said compressor through said outdoor heat exchanger to said indoor heat exchanger or through said indoor heat exchanger to said outdoor heat exchanger, whereby said indoor heat exchanger can be connected in parallel refrigerant flow relationship with either said evaporator or said condenser.

4. In air conditioning apparatus including a compression refrigeration system, a compressor having an inlet and an outlet, an indoor heat exchanger, an outdoor heat exchanger, means including a bidirectional expansion device connecting said outdoor heat exchanger to said indoor heat exchanger and permitting refrigerant flow in either direction from one to the other of said heat exchangers, means including a reversing valve for selectively connecting the outlet of said compressor to said outdoor heat exchanger and the inlet of said compressor to said indoor heat exchanger or the outlet of said compressor to said indoor heat exchanger and the inlet of said compressor to said outdoor heat exchanger, an evaporator, a con-

denser, means connecting said compressor, condenser, and evaporator for routing refrigerant from said compressor through said condenser to said evaporator regardless of the condition of said reversing valve, means for circulating indoor air over said indoor heat exchanger and said evaporator, and means for circulating outdoor air over said outdoor heat exchanger and said condenser.

5. In air conditioning apparatus including a compression refrigeration system, a compressor having an inlet and an outlet, an indoor heat exchanger, an outdoor heat exchanger, means including a bidirectional expansion device connecting said outdoor heat exchanger to said indoor heat exchanger and permitting refrigerant flow in either direction from one to the other of said heat exchangers, means including a reversing valve for selectively connecting the outlet of said compressor to said outdoor heat exchanger and the inlet of said compressor to said indoor heat exchanger or the outlet of said compressor to said indoor heat exchanger and the inlet of said compressor to said outdoor heat exchanger, an evaporator disposed adjacent said indoor heat exchanger, a condenser disposed adjacent said outdoor heat exchanger, means connecting said compressor, condenser, and evaporator for routing refrigerant from said compressor through said condenser to said evaporator regardless of the condition of said reversing valve, means for circulating indoor air first over said evaporator and then over said indoor heat exchanger, and means for circulating outdoor air first over said condenser and then over said outdoor heat exchanger.

6. In a refrigeration circuit for air conditioning apparatus, a compressor having an inlet and an outlet, first and second indoor heat exchangers, first and second outdoor heat exchangers, means including an expansion device connecting the first outdoor heat exchanger to the first indoor heat exchanger, conduit means connecting the outlet of said compressor to said first outdoor heat exchanger and the inlet of said compressor to said first indoor heat exchanger, means including a bidirectional expansion device connecting said second outdoor heat exchanger to said second indoor heat exchanger and permitting refrigerant to flow in either direction from one to the other of said second heat exchangers, and means including a reversing valve for selectively connecting the outlet of said compressor to said second outdoor heat exchanger and the inlet of said compressor to said second indoor heat exchanger or the outlet of said compressor to said second indoor heat exchanger and the inlet of the compressor to said second outdoor heat exchanger.
